(57) **CLAIM**

The ornamental design for a toy nose as shown and described.

DESCRIPTION

FIG. 1 is an isometric view of an embodiment of a toy nose in a closed position and showing our new design;
FIG. 2 is a right side view of the toy nose of FIG. 1;
FIG. 3 is a left side view of the toy nose of FIG. 1;
FIG. 4 is a top view of the toy nose of FIG. 1;
FIG. 5 is a bottom view of the toy nose of FIG. 1;
FIG. 6 is a rear view of the toy nose of FIG. 1;
FIG. 7 is a front view of the toy nose of FIG. 1;
FIG. 8 is an isometric view of the toy nose of FIGS. 1-7 in a partially open position and showing our new design;

(Continued)

FIG. 9 is a left side view of the partially open toy nose of FIG. 8;

FIG. 10 is a right side view of the partially open toy nose of FIG. 8;

FIG. 11 is a top view of the partially open toy nose of FIG. 8;

FIG. 12 is a bottom view of the partially open toy nose of FIG. 8;

FIG. 13 is a rear view of the partially open toy nose of FIG. 8;

FIG. 14 is a front view of the partially open toy nose of FIG. 8;

FIG. 15 is an isometric view of the toy nose of FIGS. 1-14 in a fully open position and showing our new design;

FIG. 16 is a left side view of the fully open toy nose of FIG. 15;

FIG. 17 is a right side view of the fully open toy nose of FIG. 15;

FIG. 18 is a top view of the fully open toy nose of FIG. 15;

FIG. 19 is a bottom view of the fully open toy nose of FIG. 15;

15;

FIG. 20 is a rear view of the fully open toy nose of FIG. 15; and,

FIG. 21 is a front view of the fully open toy nose of FIG. 15.
